UNITED STATES PATENT OFFICE.

LESTER O. MARSTELLER, OF WILKINSBURG, PENNSYLVANIA, ASSIGNOR TO WESTINGHOUSE ELECTRIC & MANUFACTURING COMPANY, A CORPORATION OF PENNSYLVANIA.

RADIO RECEIVING APPARATUS.

Application filed August 22, 1922. Serial No. 583,575.

My invention relates to radio apparatus and particularly to radio receiving apparatus.

The principal object of my invention is 5 to provide means adapted for embodiment in regenerative wireless receiving systems wherein it may be desirable to effect a substantial increase in the wave length of the system over that determined by the original 10 design thereof without altering the regenerative characteristics of the system.

Another object of my invention is to provide apparatus for accomplishing the above-mentioned desired result which is of simple, 15 compact and rugged design suitable for inexpensive quantity-production methods of manufacture and comprising parts which may be easily made in simple automatic machinery and may be readily assembled 20 with a minimum expenditure of time and money.

A more specific object of my invention is to provide apparatus of the class described comprising a casing enclosing a loading coil 25 and tickler coil disposed in spaced inductive relation and having a plurality of supporting feet which constitute the terminal connectors for the coils and which provide a space intermediate the casing and the planes 30 of the feet which is adapted to receive a switching mechanism for short circuiting or open circuiting the coils through their corresponding terminal connectors.

With these and other objects and applications in view, my invention further consists in the details of construction and circuit arrangement hereinafter more fully described and claimed and illustrated in the accompanying drawing wherein—

40 Figure 1 is a side elevational view of a structure embodying my invention;

Fig. 2 is a longitudinal sectional view of the structure of Fig. 1 taken on the line II—II thereof.

45 Fig. 3 is a bottom plan view of the structure of Fig. 1;

Fig. 4 is a diagrammatic view of circuits and apparatus embodying my invention and illustrating the application thereof to a 50 wireless receiving system of standard design;

Fig. 5 is a rear elevational view showing a wireless cabinet adapted to embody the circuit arrangement of Fig. 4 and illustrat-

ing one method of applying the structure 55 of the foregoing figures to a wireless receiving cabinet.

In the illustrated embodiment of my invention shown in the drawing, a molded casing 1 is provided having ends 2 and 3 60 and a substantially flat base 4 and it is supported by a structure 5, as hereinafter described. The casing provides a chamber 6 of cylindrical shape which is open at one end or side 3 and closed at the other end or side 2. A post 7 is centrally positioned in the chamber 6 and has one end rigidly secured to the closed side 2 of the chamber 6 by means of a screw 8.

A pair of inductive reactance elements 9 70 and 11, which, for the purpose of illustration, are shown in the form of spirally wound coils having terminal leads 12, 13 and 14, 15, respectively, are mounted upon the post 7 in mutually inductive relation. The coils 9 and 11 are designed to serve, respectively, as a loading coil and as a tickler coil, as hereinafter explained. The open end 3 of the casing 1 may be closed by means of a member 16 of disk shape which 80 may be secured in position by means of a screw member 17 extending through the disk 16 and engaging the unsupported end of the post 7.

The supporting structure 5 for the casing 1 is of such design as to provide combined supporting feet and circuit terminals for the coils 9 and 11 and to provide a switching mechanism for open circuiting or short circuiting the terminals of the several coils 90 through their respective supporting feet.

The desired result is accomplished by providing two pairs of switch units 18 and 19, which also serve as terminal connectors for the coils 9 and 11, respectively. The two pairs of units comprise members 21, 22 and 23, 24, respectively. Each of the members just mentioned has a horizontally extending portion 25 which is secured to the base 4 by screws 26 and 27 in spaced relation. The screws 27 may extend through the molded casing 1 into the chamber 6 to provide connections between the several coil terminals and the individual members of the several switch units.

The outer end of the horizontally extending portion may be provided with a bent-back portion 28 extending vertically there-

from and terminating in an oppositely extending horizontal portion 29 which is designed to serve as a supporting foot and as a connector, as, for instance, in the manner shown in Fig. 5. To this end, the lateral extension 29 is provided with a perforation 31 for receiving a binding post 32 of a receiving cabinet 33.

Corresponding elements 21 and 23 of the switch units 18 and 19, respectively, are provided with pivotally mounted switch arms 34 and 35, the ends of which may engage stationary contact elements 36 and 37, which are secured to the remaining elements 22 and 24, respectively. Each of the stationary contact elements 36 and 37 may be constructed by bending a strip integral with the corresponding element 22 or 23 to provide jaws for receiving the end of the corresponding movable contact elements 34 or 35, as shown in Fig. 1. However, if desired, the jaws may be constructed separately and secured to the elements 22 and 24 by means of the screws 27.

25 A switch rod 38 for opening and closing the switch units 18 and 19, as hereinafter explained, is slidably mounted between the inner edges of the several horizontally extending portions 25 and is constrained to move in a longitudinal direction by the same. A strip member 39, which is secured to the under side of the casing 4 by screws 41 at a point substantially midway between the switch units 18 and 19, serves to provide additional limiting means for constraining the motion of the rod 38 to a longitudinal direction only. Operation of the movable contact elements 34 and 35 of the switch units 18 and 19 is effected by means of pins 42 and 43 carried by the switch rod 38 and engaging slotted portions 44 and 45 in the movable contact elements 34 and 35, respectively.

When the switch rod 38 is moved to actuate the ends of the movable contact elements 34 and 35 into engagement with the jaws formed by the stationary contact elements 36 and 37, the opposite terminals of each coil 9 and 11 are electrically connected and hence the coils are short circuited. When the switch rod 38 is moved in an opposite direction to actuate the movable contact elements 34 and 35 out of engagement with the stationary contact elements 36 and 37, the short-circuiting connections are broken.

55 Fig. 4 shows a practical embodiment of my invention in a wireless receiving system employing the so-called "single-circuit receiver", the general features of which constitute the subject matter of a copending application of Frank Conrad, Serial No. 386,323, filed June 3, 1920, and assigned to the Westinghouse Electric & Manufacturing Company. My invention, however, is not necessarily limited to any particular type of regenerative receiving circuit.

In the circuit arrangement herein shown, an antenna 46 is connected to ground through a variable condenser 47, a variometer 48, the switch unit 19 and a ground conductor 49. The condenser 47 and variometer 48 are mechanically connected by means of a connecting member 50, whereby tuning is effected by the adjustment of both the condenser and the variometer for a purpose which will appear hereinafter. 75

A three-electrode-tube 51, containing a grid 52, a hot cathode 53 and an anode 54 therein, has its grid input electrode 52 connected through a condenser 55 and a grid leak 56, to a point in the antenna circuit intermediate the variable condenser 47 and the variometer 48. The cathode 53 of the tube 51 is connected to the grounded side of the switch unit 19 by a conductor 57. A plate-filament circuit for the tube 51 is inductively coupled to the variometer 48 by means of a coil 58 in such manner as to admit of regeneration and may include, in addition, the remaining switch unit 18 of the switch mechanism shown in the foregoing figures. 90

When receiving on wave-lengths included within the normal range of the regenerative receiving set, the switches 18 and 19 of my auxiliary loading coil apparatus, are closed, thus short circuiting the auxiliary loading coil 9 in the antenna circuit and the auxiliary tickler coil 11 in the plate feed-back circuit, respectively. Tuning is effected by simultaneously adjusting the variometer 48 and the tuning condenser 47 in such manner as to 95 maintain a suitable amount of feed-back coupling for regenerative reception of any wave-length within the range of the receiving apparatus.

In order to secure regenerative reception 105 of signals at wave lengths longer than the longest wave for which the receiving apparatus was designed, it has been found that satisfactory operation may be effected by means of an auxiliary loading coil, as 9, inserted in the antenna circuit and a suitably proportioned auxiliary tickler coil, as 11, inserted in the plate circuit in proper inductive relation to the auxiliary loading coil. The necessary proportions and arrangements of 110 the auxiliary apparatus depend upon the constants of the particular regenerative receiving set for which the auxiliary loading coil is designed. In general, it may be stated that when the wave length is increased, the 115 feed-back coupling must also be increased, and my tuning-coil apparatus is designed to meet this need in the art of regenerative radio reception. 120

An arrangement shown in Fig. 5 illustrates one method of applying my invention to the wireless receiving cabinet 33 embodying a receiving system such as that of Fig. 4, the wave length of which is too low. It will be noted that the several supporting feet for 125 130

the casing 1 are electrically connected to the binding posts 32 of the cabinet 33 and supported thereby.

While I have shown but one embodiment 5 of my invention for the purpose of describing the same and more fully illustrating its principles of operation and its construction of details, it is apparent various changes and modifications may be made in the nature, the 10 mode of operation and the details of construction without departing from the spirit of my invention. I desire, therefore, that only such limitations shall be imposed thereon as are indicated in the appended claims or 15 demanded by the prior art.

I claim as my invention:

1. In combination, a casing adapted to embody electrical apparatus, and a plurality of supporting feet for said casing providing 20 a space between the casing and the plane of the feet, certain of said feet constituting terminal connectors for said apparatus, and a switch mechanism disposed in said space.

2. In combination, a casing, electrical apparatus disposed therein, and a plurality of supporting feet for said casing providing a space between the casing and the plane of 25 said feet, certain of said feet constituting terminal connectors for said apparatus, and means carried by said casing and extending 30 into said space for, at will, close circuiting said electrical apparatus through said terminal connectors.

3. In combination; a casing, a pair of inductive reactance elements suitably disposed 35 therein, a plurality of pairs for supporting feet for said casing, each pair of feet constituting the terminal connectors for one of said inductive reactance elements, and 40 switching means for short circuiting said elements through corresponding pairs of terminal connectors.

4. In combination, a regenerative electrical system, a casing, a loading coil and a 45 tickler coil suitably mounted in said casing in such relation to said system as to admit of substantially no change in the tendency for said system to regenerate upon the inclusion of said coils therein, and a plurality 50 of pairs of supporting feet for said casing, each pair of feet constituting the terminal connectors for one of said coils.

5. In combination, a casing, a pair of inductive reactance elements of predetermined 55 proportions suitably mounted therein in spaced relation, a plurality of supporting feet for said casing constituting terminal connectors for said elements, means adapted to receive said supporting feet, said feet being of such design as to provide an open 60 space between the casing and the supporting means, and means disposed in said space for short circuiting said elements through their corresponding terminal connectors.

6. In combination, a casing having an

opening in one side thereof, a member rigidly positioned in substantially the axis of said opening an inductive reactance element carried by said member, a plurality of supporting feet for said casing, certain of said 70 feet constituting terminal connectors for said element, means adapted to receive said supporting feet, and means for short circuiting, at will, said element through its terminal connectors. 75

7. In combination, a casing having an opening in one side thereof, a member having one end secured to the opposite side and substantially centrally positioned, an inductive reactance element carried by said member, a closure for said opening and a plurality of supporting feet for said casing, certain of said feet constituting terminal connectors for said element. 80

8. In combination, a casing having an 85 opening in one side thereof, a member having one end secured to an opposite side and substantially centrally positioned, an inductive reactance element carried by said member, means for closing said opening, a connector for engaging said means and the other end of said member in such manner as to secure said means in position, and a plurality of supporting feet constituting 90 terminal connectors for said element. 95

9. In combination, a casing having an opening in one side thereof, a member having one end secured to an opposite side and substantially centrally positioned, a pair of inductive reactance elements carried by said 100 member, means for closing and opening, a plurality of supporting feet for said casing constituting terminal connectors for said elements, said feet being of such design as to provide an open space between the casing 105 and the plane of the feet, and means carried by said casing and extending down into said space for short circuiting, at will, said elements through their corresponding terminal connectors. 110

10. The combination with apparatus having terminal connectors positioned in one surface thereof, of co-operating apparatus comprising a casing having inductive reactance elements mounted therein, supporting feet for said casing constituting terminal connectors for said elements, said feet being supported by said first-mentioned terminal connectors and embodying such design as to provide a space between said 115 casing and said first-mentioned apparatus, and means carried by said co-operating apparatus and disposed in said space for short circuiting, at will, said elements through their corresponding terminal connectors. 120

11. The combination with apparatus having terminal connectors positioned in one surface thereof, of co-operating apparatus comprising a casing having inductive reactance elements mounted therein, a plural- 125 130

1. The combination with an electrical apparatus, of a plurality of supporting feet insulated from one another and electrically connected to the respective terminals of said apparatus, and switching means for providing a short-circuiting connection or connections between said feet.
2. The combination with an electrical apparatus, of a plurality of supporting feet insulated from one another and electrically connected to the respective terminals of said apparatus, and switching means for providing a short-circuiting connection or connections between said feet, said switching means comprising movable contact elements, stationary contact elements and a switch rod for actuating the movable contact elements into engagement with the stationary contact elements and vice versa.
3. The combination with an electrical apparatus, of a plurality of supporting feet insulated from one another and electrically connected to the respective terminals of said apparatus, and switching means for providing a short-circuiting connection or connections between said feet, said switching means comprising movable contact elements, stationary contact elements and a switch rod for actuating the movable contact elements into engagement with the stationary contact elements and vice versa, and means carried by said co-operating apparatus and disposed in said space for short circuiting, at will, said elements through their corresponding terminal connectors.
4. The combination with a main electrical apparatus having terminal binding posts, of an auxiliary electrical apparatus having a plurality of supporting feet insulated from one another and electrically connected to the respective terminals of said auxiliary apparatus, said supporting feet being provided with openings for engaging said binding posts.
5. The combination with an electrical apparatus, of a plurality of supporting feet insulated from one another and providing a space adjacent to the base of said apparatus, means for electrically connecting one or more of said feet to said apparatus, means for electrically connecting one or more of said feet to an electric circuit or circuits, and a switching mechanism mounted in said space.
6. The combination with a main electrical apparatus having two pairs of juxta-positioned binding posts adapted to be interconnected in pairs, of an auxiliary electrical apparatus connected in circuit with said binding posts, and switching mechanism for providing short-circuiting connections interconnecting said binding posts in pairs.
7. The combination with a main electrical apparatus having two pairs of juxta-positioned binding posts adapted to be interconnected in pairs, of a switching mechanism having insulated supporting feet provided with openings for energizing said binding posts, conductors connected to said feet and adapted to connect auxiliary apparatus, and means for providing short-circuiting connections interconnecting said feet in pairs.
8. A switching unit comprising a longitudinally reciprocable operating rod, a pair of insulated supporting feet disposed on opposite sides of the line of movement of said rod, means for electrically connecting said feet to an external circuit, a switch-arm pivoted to one of said feet and adapted to be moved into engagement with the other of said feet, and an operative connection between said switch-arm and said rod.
9. The combination with a regenerative apparatus including an amplifier, input and output circuits therefor and means for returning some of the power from the output circuit to the input circuit, of a loading coil in said input circuit, a tickler coil in said output circuit in inductive relation to said loading coil, a housing containing said two coils, supporting means for said housing constituting the terminals of said coils and a switching device cooperating with said terminals for short-circuiting both of said coils simultaneously at will.
10. In a radio receiving system, a regenerative detector, auxiliary means including a loading coil and a supplemental tickler coil, conductive securing devices for attaching said auxiliary means to said regenerative detector and connections whereby said securing devices will put said loading and supplemental tickler coils in circuit with the corresponding parts of the regenerative detector.
11. In a radio receiving system, a regenerative detector, auxiliary means including a loading coil and a supplemental tickler coil, conductive securing devices for attaching said auxiliary means to said regenerative detector and connections whereby said securing devices will put said loading and supplemental tickler coils in circuit with the corresponding parts of the regenerative detector, and a switching device for simultaneously short-circuiting said loading and supplemental tickler coils.
12. In testimony whereof, I have hereunto subscribed my name this 15th day of August, 1922.

LESTER O. MARSTELLER.
